DESIGN FOR AN ELECTRIC CUBE TAP

Louis Ludwig, New York, N. Y.

Application July 15, 1948, Serial No. 147,572

Term of patent 14 years

(Cl. D26—1)

To all whom it may concern:

Be it known that I, Louis Ludwig, a citizen of the United States of America, residing in the Borough of Queens, city of New York, county of Queens, and State of New York, have invented a new, original, and ornamental Design for an Electric Cube Tap, of which the following is a specification, reference being had to the accompanying drawing, forming part thereof.

Figure 1 is a view in perspective of an electric cube tap, showing my new design, showing front, top, and one side.

Figure 2 is an elevational view, showing another side of the electric cube tap shown in Figure 1.

Figure 3 is a rear elevational view of the tap shown in Figure 1.

Figure 4 is a bottom plan view of the tap shown in Figure 1.

I claim:

The ornamental design for an electric cube tap, as shown.

LOUIS LUDWIG.
